UNITED STATES PATENT OFFICE.

ADOLF SCHWIEGER, OF HANOVER, GERMANY.

CIGAR-CASE.

1,021,849.

Specification of Letters Patent.

Patented Apr. 2, 1912.

Application filed November 5, 1910. Serial No. 590,950.

To all whom it may concern:

Be it known that I, ADOLF SCHWIEGER, a subject of the Emperor of Germany, residing at Hanover, in Germany, have invented certain new and useful Improvements in Cigar-Cases, of which the following is a specification.

This invention relates to cigar cases, and substantially consists in combining cigar cases combined with appliances for lighting cigars and cigarettes and for cutting off the tips of cigars.

Several embodiments of the invention are shown in the accompanying drawing in which—

Figure 1 is a perspective elevation of a case wherein the cutter forms part of the fastening. Fig. 2 shows part of a case with cutter pivoted to the frame thereof. Fig. 3 shows a cutter attached to a case of another type, and serving as a fastening for same.

Referring in the first place to Fig. 1, the knife *a* comprises a blade which is adapted to enter a slot *b* in the frame 2 of the case, said blade being formed on a springy shank 3 fixed to the same frame part. The rear or lower end of the shank 3 forms a catch *c* adapted to engage the slotted part *d* of the frame-part 4. A match-holder *e* adapted to contain a flat strip of matches is attached to the case, and has a flexible cover *f* provided with a lug *h*, which is adapted to enter a slot *g* for fastening purposes.

In Fig. 2 the cutter *a* is pivoted to the frame 5, the part to which it is pivoted having a gap 6 which forms a seat for the cigar-end to be cut. A similar seat may be formed on the opposite frame-part 7, to register with the seat 6 when the case is closed.

Fig. 3 shows the cutter *a* pivoted to a metal mount 8 on one lip of the mouth of the case, the latter being of the bag type. The cutter is bent to extend across the

mouth, so that the blade descends on the opposite side of a mount 9 fixed to the other lip. A catch 10 at the free end of the cutter is adapted to embrace both the mounts 8 and 9, and thus close the case, the fastening being made by the act of using the cutter.

Many other modifications are possible within the scope of the invention. A match-holder may be used in conjunction with any of the cutters illustrated, or may be dispensed with.

What I claim as my invention and desire to secure by Letters Patent of the United States is:

1. In combination with a cigar case, a cigar cutter disposed on the edges thereof and comprising a shank pivotally secured to said case, a knife disposed at one end of said shank and arranged to move in and out of a slot provided in one of said edges, said shank being provided with means for locking said edges together after said knife is disposed within said slot.

2. In combination with a cigar case, a cigar cutter disposed on the inner edge portion thereof and comprising a shank pivotally mounted thereon, a cigar knife integrally connected to the end of said shank and arranged to move in and out of a slot provided in the edge portion of said cigar case that the shank is attached to, a lock integrally mounted at the other end of said shank and arranged to actuate within a slot provided in the opposite edge portion of said case, said lock being provided with a resilient hook arranged to engage with the outside surface of said case when said cigar case is closed, substantially as described.

In witness whereof I have signed this specification in the presence of two witnesses.

ADOLF SCHWIEGER.
